US0D1050854S

(12) **United States Design Patent** (10) **Patent No.:** **US D1,050,854 S**
(45) **Date of Patent:** **** Nov. 12, 2024**

(54) **CODE LOCK**

(71) Applicant: **Haoran Wang**, Zhejiang (CN)

(72) Inventor: **Haoran Wang**, Zhejiang (CN)

(73) Assignee: **Haoran Wang**, Yiwu (CN)

(**) Term: **15 Years**

(21) Appl. No.: **29/882,291**

(22) Filed: **Jan. 12, 2023**

(51) **LOC (14) Cl. 08-07**

(52) **U.S. Cl.**

USPC **D8/334**

(58) **Field of Classification Search**

USPC D8/330, 331, 333, 334, 336, 339

CLAIM

The ornamental design for a code lock as shown and described.

DESCRIPTION

FIG. 1 is a front, right perspective view of the code lock;

FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the code lock that form no part of the claimed design.

1 Claim, 8 Drawing Sheets
